[57] CLAIM

The ornamental design for a solid ink stick for a color printer, as shown and described.

DESCRIPTION

FIG. 1 is a perspective view of a solid ink stick for a color printer showing the top surface;

FIG. 2 is a top plan view thereof;

FIG. 3 is a side elevational view thereof, the opposite side being identical; and,

FIG. 4 is an end elevational view thereof, the opposite side being identical.

The broken line portions of FIGS. 1, 3 and 4 are for purposes of illustration only and form no part of the claimed design.
